UNITED STATES PATENT OFFICE.

JULIAN L. DODGE, OF CHICAGO, ILLINOIS, ASSIGNOR TO ALEXANDER PRUSSING AND MARY R. DODGE, OF SAME PLACE.

METER.

SPECIFICATION forming part of Letters Patent No. 599,494, dated February 22, 1898.

Application filed July 8, 1897. Serial No. 643,790. (No model.)

To all whom it may concern:

Be it known that I, JULIAN L. DODGE, a citizen of the United States, residing at Chicago, in the county of Cook and State of Illinois, 5 have invented and produced new and useful Improvements in Meters, of which the following is a specification.

My invention relates to meters for measuring water and the like, and has for its object 10 to provide a new and improved meter, of which the following is a description, reference being had to the accompanying drawings, wherein—

Figure 1 is a view in part section of a water-meter embodying my invention. Fig. 2 is a 15 plan view of the disk of a water-meter shown in position. Fig. 3 is a section on line 3 3, Fig. 1, with parts omitted. Fig. 4 is a vertical section through a portion of the disk-chamber of the meter, the disk being removed. 20 Fig. 5 is a plan view of a portion of one of the end pieces of the disk-chamber.

Like letters refer to like parts throughout the several figures.

Disk-meters as heretofore constructed have 25 been provided with a movable disk, usually of hard rubber and located in a disk-chamber provided with a division-plate, the disk being cut away or slotted to receive this division-plate. It has been found in practice that the 30 cutting away of this disk for the division-plate weakens the disk to such an extent that it is often broken by the force of the water entering the meter. This breakage of the disk is particularly liable to happen after the 35 parts have become somewhat worn, so that the contact of the disk with the division-plate produces a vibrating or chattering effect when the disk is moved.

One of the objects of my invention is to 40 provide a disk-meter so constructed that the liability to breakage of the disk will be lessened.

Referring to the accompanying drawings, I provide a disk A of any suitable material— 45 as, for example, hard rubber—provided with the ball-shaped central piece A⁴ and mounted in the disk-chamber A' in the ordinary manner or in any other suitable way. The disk A is a continuous disk, the division-plate be- 50 tween the inlet and outlet of the meter being connected therewith. This division-plate

may be of any suitable material and may be constructed in any suitable manner. As illustrated in the drawings, said division-plate is provided with a curved edge B', preferably 55 the arc of a circle. The division-plate is provided with some suitable guiding or holding device for holding it against lateral movement. As illustrated in the drawings, the curved edge B' of the division-plate works in a slot 60 B² in the disk-chamber or some part associated therewith. This division-plate, as illustrated in the drawings, consists of two parts, one above and one below the disk, the parts being connected with the disk so that 65 said disk is free to move with relation thereto. I prefer to have these parts of the division-plate pivoted so as to rock or move about a center substantially in the plane passing through the middle portion of the disk. 70

As illustrated in the drawings, the disk A is provided with the projecting parts A³, so as to be formed thicker at the point where the division-plate is connected. These projecting parts are preferably rounded, and the 75 parts of the division-plate are formed so as to fit these rounded portions in order to make a comparatively tight joint. It is of course evident that the joint may be made in any other suitable manner. The parts of the di- 80 vision-plate, as illustrated in the drawings, are rigidly connected together by the pieces B³, said pieces being pivotally connected to the pin B⁴, located near the middle of the disk. The pieces B³ are held in place by 85 means of the pins B⁵. By this construction the disk is free to move when the division-plate is held against lateral motion. The cones or end pieces C of the disk-chamber are each provided with a slot C', through 90 which the portions of the division-plate project as the plate is reciprocated by the movement of the disk. I prefer to form a separable disk-chamber, as shown, so that the disk may be easily placed in position. I also pre- 95 fer to form the inlet and outlet passage-ways for the water in the walls of the disk-chamber, as illustrated at C³ in Fig. 2. The chambers D and D' on each side of the disk-chamber are preferably connected with the disk-chamber or the inlet or outlet passage-ways— 100 as, for example, by openings D² at the side of

the disk-chamber—so as to equalize the pressure above and below the disk, the disk being suspended, as it were, in the water. The disk-pin E of the disk is connected with the 5 meter-shaft E' in the ordinary manner, so as to rotate the same, and bears against the cone E². This cone E² is elastically connected with the shaft E' in any suitable manner, so that it may have a certain amount of lateral motion in order to prevent the binding of the parts when the shaft E' is not accurately alined. This elastical connection may be formed in any convenient manner, and, as shown in the drawings, consists of an elastic 10 washer E³, interposed between the cone and the shaft. It will be seen that by this construction as the disk A moves the division-plate, although held from lateral motion by its engagement with the meter-case, 15 is so connected with the disk as to allow said disk to move with relation thereto and acts in all respects, so far as the operation of the meter is concerned, as though it were stationary and rigidly connected with the disk-case, 20 the disk being cut away so as to receive it, as in the ordinary meter. It will also be seen that by this construction danger of the breakage of the disk by the impact or "hammer" 25 of the water is greatly lessened, as the disk is continuous throughout and able to withstand any force which may be applied to it in the working of the meter.

I have not illustrated the remaining mechanism of the meter for the reason that such 35 mechanism is no part of my present invention and may be of any suitable description.

I have described in detail a particular construction embodying my invention in order 40 to make its application clear; but I wish it to be understood that I in no manner limit myself to this particular construction, for it is evident that the construction and arrangement of the various parts may be greatly modified without in any manner departing 45 from the spirit of my invention.

I claim—

1. A meter comprising a continuous disk, a disk-chamber in which said disk is movably mounted, said disk-chamber provided with an 50 inlet and outlet for the fluid to be measured, and a division-plate interposed between said inlet and outlet.

2. A meter comprising a disk movably mounted in a disk-chamber, provided with an 55 inlet and an outlet for the fluid to be measured, and a movable division-plate intermediate between said inlet and outlet adapted to be moved during the operation of the meter.

60 3. As an article of manufacture, a disk for water-meters, comprising a disk proper adapted to be movably mounted in the meter-case, said disk provided with a reciprocating di-

vision-plate connected thereto, so as to move therewith. 65

4. As an article of manufacture, a disk for water-meters, comprising a disk proper adapted to be movably mounted in the meter-case, and a division-plate pivotally connected with said disk. 70

5. As an article of manufacture, a disk for water-meters, comprising a disk proper having a substantially continuous surface, a two-part division-plate, one part on each side of said disk, a connecting-piece passing through 75 the disk and connecting the two parts of the division-plate together, said connecting-piece pivotally connected with the disk.

6. A meter comprising a movable disk, a disk-chamber in which said disk is mounted, 80 a reciprocating division-plate connected with said disk so as to be moved thereby, and a guide for said division-plate associated with said disk-chamber.

7. A meter comprising a disk having a motion of nutation, a disk-chamber in which said disk is mounted and provided with an inlet and outlet for the fluid to be measured, a division-plate interposed between said inlet and outlet and connected with said disk, and a 90 slot or opening in the top and bottom of said disk-chamber through which said division-plate projects. 85

8. A meter comprising a continuous movable disk, a disk-chamber in which said disk is mounted, 95 said disk-chamber provided with an inlet and outlet for the fluid to be measured, a division-plate connected with said disk and interposed between the inlet and outlet, and a guiding or holding device for 100 said division-plate to hold it against lateral movement.

9. A meter comprising a substantially continuous movable disk, a disk-chamber in which said disk is mounted, said disk-chamber provided with an inlet and outlet for the fluid to be measured, a two-part division-plate, one part on each side of said disk, a connecting-piece passing through the disk and connecting the two parts of the division-plate together, 110 said division-plate pivotally connected with the disk and interposed between the inlet and outlet, and a guiding device for said division-plate associated with the disk-chamber. 115

10. As an article of manufacture, a disk for water-meters, comprising a disk proper having a substantially continuous periphery and adapted to be movably mounted in a meter-case, said disk provided with a division-plate 120 connected thereto so as to move therewith.
